UNITED STATES PATENT OFFICE.

GEORGE L. BALLARD, OF NORRISTOWN, PENNSYLVANIA, ASSIGNOR TO WILDMAN MFG. CO., OF NORRISTOWN, PENNSYLVANIA, A CORPORATION OF PENNSYLVANIA.

CLOTH-CUTTING MACHINE.

1,282,669.

Specification of Letters Patent. Patented Oct. 22, 1918.

Application filed January 13, 1917. Serial No. 142,220.

To all whom it may concern:

Be it known that I, GEORGE L. BALLARD, a subject of the King of Great Britain, and resident of Norristown, Pennsylvania, have 5 invented certain new and useful Improvements in Cloth-Cutting Machines, of which the following is a specification.

The invention consists in the features and combination and arrangement of parts here- 10 inafter described and particularly pointed out in the claims, some of the features relating to the general organization of the machine.

In the accompanying drawings:

15 Figure 1 is a central vertical sectional view of the machine.

Fig. 2 is a front view with the pressure foot and its support swung aside and exposing the cross head, crank and adjacent 20 parts.

25 The object of the invention is to provide a cloth cutting machine driven by an alternating current motor and in which the cutter will be of the reciprocatory type.

It is desirable to employ an alternating 30 current motor because of the more general availability of current of this character, but the speed of such motor being dependent upon the speed of the generator is objectionable in connection with a reciprocating knife, unless special provision is made for the transmission of the power to the knife.

In order to attain high production with 35 a reciprocating knife it is desirable to have the stroke thereof of the maximum length, say one inch and five-eighths (1 $\frac{5}{8}$ "), but a stroke of this length under high speed, such as an alternating current motor would ordinarily impart, is objectionable, because of 40 the excessive wear particularly on the crank pin and cross head connection. In order to meet the difficulties I have provided a construction in which the knife has a long or maximum stroke, but is driven at a reduced 45 speed in respect to the speed of revolution of the alternating current motor.

The motor has its armature on a vertical shaft 1 and the field coil surrounds this armature, being concentric therewith. The 50 reciprocating knife 2 is carried by a cross head 3 moving on guide rods 4 held at their upper ends in an upper housing member 5 and at their lower ends in a plate 6 secured to a lower housing member. These housing 55 members are held together by bolts 7 and

they clamp between them the field coil of the motor. The cross head is reciprocated by a pitman 8 connected to a crank 9 on a shaft 10, which is journaled in bearings formed with or supported on the upper 60 housing member 5. This shaft is driven by a gear 11 on the vertical shaft of the armature meshing with a gear 12 on the shaft, said gear 12 being arranged at the right of the gear 11 and between it and the bearing 65 in which the shaft 10 is journaled. This gearing constitutes reduction driving means for the knife which, therefore, instead of working at 3600 strokes a minute for 3600 revolutions of the armature is reciprocated 70 at 2600 strokes per minute for the high speed of the armature above mentioned, and this slower movement of the knife renders it possible to give to the knife a stroke of the desired length, say one and five-eighths 75 inches (1 $\frac{5}{8}$ "), thus preventing undue wear on the bearings, which would otherwise be caused by the thrusts of the reciprocating parts.

The upper housing section not only carries the bearings for the horizontal transmission shaft, but it has an extension housing 13 forming the casing for the crank and it has the bearing for the upper portion of the vertical armature shaft. Further, it 80 has the upper bearing 14 of the hinged front plate 15, which carries the presser foot. The lower housing section besides carrying the lower bearing for the vertical shaft of the armature carries a bracket 16 85 formed therewith and extending forward from the housing. This bracket is connected or formed with the post or standard 17 in which the reciprocating knife is guided.

The presser foot may be of any suitable 90 variety. As shown, it comprises a rod 17 carrying the foot plate 18 at its lower end, which has a slot to receive the knife, and this rod is suitably mounted on the outer or front side of the front plate. This front 95 plate covers the power transmitting mechanism, consisting of the crank, the pitman, the cross head and associated parts, and by throwing this front plate aside, on its hinge connection the presser foot is removed from 100 the knife and further the parts just described are made accessible.

It will be noted that the motor, including the armature and its field, is located in rear of the knife and the transmitting mecha- 110

nism leaving the front of the machine free. The two part housing clamping the field of the motor in place and providing as to the upper section, the bearings for the shaft-
5 ing, the crank casing, and part of the hinge support for the swinging front plate, and as to the lower section providing the lower bearing 20 for the armature shaft the bracket 16 for the knife guide or post and
10 the carrier for the support 6 of the cross head guides and a part 14' of the hinge connection for the front plate provides a simple compact and well balanced structure, and one capable of ready assembly.

15 I claim as my invention:

1. In combination in an electrically driven cloth cutting machine, an armature on a vertical shaft, a field coil surrounding the armature, a housing consisting of upper and lower sections, means securing said sections together, and clamping the field coil between them, the upper housing section having a bearing for the vertical shaft and bearings for a horizontal shaft and also a
25 supplemental housing for a crank, a horizontal shaft in said bearings, gearing between the said horizontal shaft and the vertical shaft, a reciprocating cutting knife, a crank in said supplemental housing and
30 on the horizontal shaft, a pitman connection between the crank and the knife, a post in which the knife is guided, the said lower housing section having a bearing for the vertical armature shaft and having a bracket

connected with the knife guide post, a front 35 plate, a presser foot carried thereby, said front plate covering the crank and the pitman connection when in normal position, said front plate being hinged to the upper and lower housing sections to be swung 40 aside to remove the presser foot from normal position, and to expose the crank and pitman, substantially as described.

2. In combination in an electrically driven cloth cutting machine, an armature, a vertical shaft carrying the same, a field coil surrounding the armature, a reciprocating knife at the front of the armature and its field coil, a cross shaft, gearing between the same and the armature shaft, a cross head 50 carrying the knife, a crank and pitman connection between the horizontal shaft and the knife cross head, and upper and lower housing sections clamping the field coil between them, and having bearings for the 55 vertical shaft, the upper section having bearings for the horizontal shaft and a supplemental housing for the crank and the lower section having a bracket, a guide post for the knife extending down therefrom, 60 guide means for the knife cross head extending between the upper and lower housing sections and means for connecting the upper and lower sections of the housing.

In testimony whereof I affix my signature.

GEORGE L. BALLARD.
